BY MacLeod, Balm, Lofland & *Attys.*

UNITED STATES PATENT OFFICE.

VINCENT P. RUMELY, OF DETROIT, MICHIGAN, ASSIGNEE TO ESSEX MOTORS, OF DETROIT, MICHIGAN, A CORPORATION OF MICHIGAN.

QUARTER PAD FOR VEHICLE TOPS.

Application filed January 30, 1922. Serial No. 532,619.

To all whom it may concern:

Be it known that I, VINCENT P. RUMELY, a citizen of the United States, residing at Detroit, county of Wayne, State of Michigan, have invented a certain new and useful Improvement in Quarter Pads for Vehicle Tops, of which the following is a specification, reference being had therein to the accompanying drawings.

10 In the building of vehicle tops, especially such tops as are commonly used on motor vehicles of the open type, it is customary to employ a pad to form a rounded corner at the junction of the deck and quarter and to give body to the latter. In the use of such a pad it is necessary that the upper or inner edge thereof be tapered off in order to prevent the formation of an abrupt shoulder in the finished top, and permit the upper surface of the deck to be smooth and unbroken. Quarter pads of this character have heretofore usually been formed during the construction of the top by inserting several layers of suitable padding material. The 15 laying and shaping of which in such a manner as to form a pad with an edge tapered off in the desired way, has occupied considerable time of skilled workmen and has therefore been expensive.

20 The present invention has for its object to provide a quarter pad which can be easily and quickly formed without the exercise of the skill required in similar pads as heretofore made, which can therefore be produced at considerably less expense than such pads, but which will be of such a form as to leave the upper surface of the deck smooth and unbroken and to give the quarter a graceful and attractive appearance.

25 The foregoing objects of the invention, together with means whereby the same may be carried into effect, will best be understood from the following description of one form or embodiment thereof illustrated in the accompanying drawings, in which—

30 Fig. 1 is a simplified side elevation of a portion of a motor vehicle provided with a top of the type in which the present invention is employed.

35 Fig. 2 is an enlarged detail section, taken substantially on the line 2—2 of Figure 1, showing one edge of the top provided with a quarter pad formed in accordance with the invention.

Fig. 3 is a still further enlarged transverse sectional view of the pad itself.

Fig. 4 is a somewhat diagrammatic sectional view illustrating the method of forming the pad.

Fig. 5 is a view similar to Figure 3, but with the layers slightly separated, showing a modified construction.

Referring to the drawings, and particularly to Figure 1, there is shown at 10 a motor vehicle body, which may be of any usual or well-known form, provided with a top 11. As is customary in such constructions, the top comprises a substantially horizontal deck portion 12 (see Figure 2) and a down-turned quarter 13 connected with the deck portion 12 by a rounded corner or edge 14, said quarter, as herein shown, comprising a separate strip of material secured to the lateral edge of the deck portion 12 by a longitudinal seam 16. Disposed beneath the rounded corner or edge 14 is the quarter pad, designated as a whole in Figure 2 by the numeral 17, said quarter pad being enclosed in a suitable envelope 15.

40 In accordance with the present invention, the quarter pad 17 is formed from a strip A of felt, wadding, or other suitable padding material, said strip being preferably of substantially constant or uniform thickness throughout its length so as to be readily obtainable in inexpensive form, and being folded longitudinally upon itself to form a pad having the desired cross-sectional form. This folding may be accomplished in a number of ways, the preferred mode being illustrated in detail in Figures 3 and 4. As shown in said figures, said strip is folded at *d* along the line of the thinner edge of the pad to form two superimposed layers *c*, *d*, the former lying at the outer side and the latter at the inner side of the finished pad. The line of the fold *b* is preferably so located, with respect to the longitudinal center or median line of strip, that the portion *c* will be of somewhat greater width transversely of the pad than the portion or layer *d*. The layers or portions *c* and *d* are preferably further folded inwardly upon themselves and toward each other along the longitudinal lines *e* and *f*, respectively, at or adjacent the lower or thicker edge of the pad, to form additional superimposed layers *g* and *h*, respectively,

the former being preferably of somewhat greater width than the latter.

It will be seen that, in this simple, easy and inexpensive manner, a pad is formed independently of the assembling of the top, and it can be inserted as a unit into its proper place in the structure. The work of forming the pad can be performed by folding machines and the time of the skilled top-maker is saved. The resulting pad is of varying thickness, or tapering cross-section, from its thicker edge *e*, *f* to its thinner edge *b*, said pad comprising four layers of material, *c*, *d*, *g*, *h*, at its thicker edge, three layers of material, *c*, *d*, *g*, at an intermediate point, and two layers, *c*, *d*, adjacent its thinner edge *b*. The latter edge may, if desired, be drawn out or thinned down, as shown in Figures 2 and 3, in such a manner as to merge with the deck and avoid any possibility of the formation of a shoulder therein, while the extreme edges *k* and *l* of the layers *g* and *h* may, if desired, be similarly thinned or flattened in order to give a smooth lateral taper to the pad as a whole.

In the modified construction shown in Figure 5, two strips of material *A'* and *A''* are employed, said strips being superimposed upon one another and placed with one edge *b'* of each adjacent the thinner edge of the pad. The strips *A'* and *A''* are folded inwardly upon themselves or toward each other along longitudinal lines *e'*, *f'* adjacent the thicker edge of the pad to form additional layers *g'* and *h'*, respectively. The lines *e'* and *f'* are preferably located each at one side of the longitudinal center or median line of the corresponding strip, so that the portions or layers *g'*, *h'* are of less width than the remaining portions of the respective strips. The layer *h'* is also preferably of less width than the layer *g'*, and to this end the total width of the strip *A'* may be greater than that of the strip *A''*. It will be seen that the finished pad shown in Figure 5 will have substantially the same advantages as, and will be substantially identical in construction with the pad shown in Figure 3 with the single exception that the free edges *b*, *b'* of the former take the place of the folded edge *b* of the latter.

The above and other advantages of the invention, as well as various further modified embodiments thereof, will be obvious or will readily suggest themselves to those skilled in the art, and it will accordingly be understood that the invention, as defined

by the claims hereunto appended, is susceptible of considerable variation from the particular construction shown and described without departing from its spirit and scope.

What I claim is:

1. In combination with an automobile top having a deck and quarter, a quarter pad positioned at the juncture of said deck and quarter and comprising a strip of padding material folded longitudinally upon itself along a line at one side of the longitudinal center thereof to form superposed layers of different widths, at least one of said layers being further folded upon itself to form an additional layer at the edge of the pad opposite said first named fold.

2. In combination with an automobile top having a deck and quarter, a quarter pad, positioned at the juncture of said deck and quarter, comprising a strip of padding material folded longitudinally upon itself to form superimposed layers, said layers being further folded upon themselves along lines located at different distances from their free edges respectively to form additional layers of different widths at the edge of said pad opposite said first named fold.

3. In combination with an automobile top having a deck and quarter, a quarter pad, positioned at the juncture of said deck and quarter, comprising a strip of padding material folded longitudinally upon itself along a line at one side of the longitudinal center thereof to form superimposed layers of different widths, said layers being further folded upon themselves to form additional layers adjacent the edge of the pad opposite said first named fold.

4. In combination with an automobile top having a deck and quarter, a quarter pad, positioned at the juncture of said deck and quarter, comprising a strip of padding material of substantially constant thickness throughout its width, said strip being folded longitudinally upon itself along a line at one side of the longitudinal center thereof to form superimposed layers of different widths, said layers being further folded inwardly or toward one another along lines located at different distances from the free edges of said layers and at the same distance from said first named fold to form additional layers of different widths between said first named layers.

In testimony whereof I affix my signature.

VINCENT P. RUMELY.
